FEEDING MEANS FOR DRILLS.

1,299,814.

Specification of Letters Patent.

Patented Apr. 8, 1919.

Application filed April 14, 1917. Serial No. 162,025.

To all whom it may concern:

Be it known that I, LEWIS C. BAYLES, a citizen of the United States, residing at Easton, in the county of Northampton and 5 State of Pennsylvania, have invented a certain new and useful Improvement in Feeding Means for Drills, of which the following is a specification.

This invention relates to percussive tools, 10 and in particular to the means for feeding and holding hammer drills to the work.

The object of this invention is to improve the present means employed for automatically feeding and holding hammer drills to 15 the work and especially that class of hammer drills in which the drilling steel is automatically rotated.

In the prior art two methods have been employed to accomplish this. The most 20 common method of feeding such tools to the work is to attach a feed cylinder and piston to the rear of the power cylinder and by supplying a portion of the actuating fluid to the feed cylinder cause the tool to be constantly forced against the work. The 25 objection to this method is the inability to use one diameter feed cylinder and piston for varying conditions. If the pressure of the motive fluid is high then a much smaller 30 feed cylinder will be required than with low pressure. A feed cylinder of suitable diameter for low pressures will, if used with high pressure, force the drill steel so hard against its work that the cutting edges of the bit 35 are soon worn away and the bit destroyed.

Again, a larger feed cylinder is required when drilling a vertical up hole than a horizontal hole, as in the former case the feed cylinder must overcome the recoil plus the 40 weight of the tool. On down holes the feed cylinder only has to overcome the recoil less the weight of the tool.

Various designs of pressure reducing valves have been tried between the supply 45 and the feed cylinder, but they all require hand adjustment each time the conditions change and are, therefore, not automatic and have proven to be unsatisfactory in meeting the varying conditions of air pressure, pitch 50 of pole, etc. The other standard method of feeding a hammer drill to the work is what is known as the "jump feed". In this method the drill carries pawls which engage the teeth of a stationary rack. When the 55 drilling steel has penetrated the rock a cer-

tain distance the hammer piston strikes the cylinder front head and drives the entire drill a tooth along the rack where the pawls hold it until the drill steel has penetrated a distance equal to the distance between adjacent teeth on the rack, when the drill is again jumped forward.

The objections to this method are that the striking of the front head by the piston damages and destroys the entire machine after 65 a short time and also the fact that a number of blows of the piston are not fully effective in performing the work of drilling. The result is that when the full power of the blow is not delivered to the drill steel the 70 drilling speed falls off. If the compression or cushion between the piston and front cylinder head is increased, the shock to the machine is reduced, but a portion of the power of the blow is absorbed in the cushion 75 and the drilling speed is reduced.

This invention is intended to overcome the above mentioned defects and to combine in one construction air feeding means and jump feeding means mutually coöperating to advance and hold the drill firmly to the work.

With the above and other objects in view, I have devised the improved hammer drill feeding means a practical embodiment of which is represented in the accompanying 80 drawings, in which,

Figure 1 is a sectional view of a percussive self rotating hammer drill and improved feeding means in place;

Fig. 2 is a plan view of a portion of the 90 drill showing some of the parts, and

Fig. 3 is a cross sectional view taken on the line 3—3 of Fig. 2.

In the construction as shown in the drawings, 1 represents the body of the self rotating percussive tool to which my improved feeding means are attached. This tool may be of any well known and common form, the form selected for illustration being of the hammer drill type in which a drill steel 100 2 is struck by a piston 3 reciprocated in a cylinder 4, these forming no part of my present invention and being shown only in outline. To the lower extremity of the body of the tool 1 is rigidly attached a rod 5 which is preferably square in section, for a purpose to be presently described. The rod 5 may be conveniently attached to the body 1 by means of a collar 6 which is clamped to the body by means of bolts 7. 110

Extending throughout the length of the rod is a fluid passage 8 which is in communication with the pressure fluid supply when the throttle valve 9 is in open position. At 5 the lower end of the rod 5 is a pressure tight piston 10 formed by collars 11 and leather cup washers 12 working in a cylinder 13 surrounding the rod 5 so that air admitted to the chamber below the piston 10 through the fluid supply passages 8 will force the body of the drill upwardly or 10 forwardly against the work. The rod 5 and cylinder 13 are of considerable length so that a wide range of drilling is accomplished without changing drill steels. From 15 the description so far it is obvious that an air feeding means has been provided which is of well known construction.

Upon one side of the rod 5, a rack 14 is 20 provided, extending substantially the length of the rod 5 and mounted on the cylinder 13 preferably at its upper end is a pawl 15 meshing with the rack 14. The pawl 15 may be of any well known form but in the 25 form shown is provided with a plurality of teeth, each meshing with a tooth of the rack in order to impart strength to the pawl and to prevent undue wear. The pawl 15 moves at an oblique angle to the rod 5 so that as 30 the pawl 15 engages the rack 14 a slight retrograde movement of the rod 5 and the body of the drill is accomplished which will effectively free the drill bit from the bottom of the hole being drilled and will thus allow 35 the drill steel to be easily rotated. In order to yieldingly hold the pawl in place a plate spring 16 and clamping clip 17 are provided.

In operation, when the throttle valve 9 is turned to admit air or other fluid under 40 pressure from the inlet 18 to the cylinder 4 to reciprocate the piston 3, the fluid is also admitted to the air feed cylinder 13. The diameter of the cylinder 13 is somewhat smaller in the present invention than in the 45 older types of air feed tools for the reason that in the older forms of air feed tools the pressure of the fluid below the piston 10 in cylinder 13 was depended upon not only to advance the drill to the work, but hold 50 it firmly against recoil. In the present invention the feed cylinder 13 is only of such diameter that the pressure of the motive fluid below the piston 10 is sufficient to carry the weight of the tool and advance 55 the tool, but not sufficient to prevent the tool jumping back from the work on account of the recoil. The drill after having been advanced to the work and having begun cutting soon cuts a chamber in advance of the 60 bit and must be advanced to take up that distance.

The feed cylinder 13 constantly exerts a forward pressure on the tool, this being sufficient to move the tool forward during the 65 rearward stroke of the piston but not enough

to hold it there when the recoil takes place during the forward stroke of the piston. This holding against backward movement is accomplished by the pawl 15 and rack 14. As soon as the forward jump of the tool between blows exceeds the distance between adjacent teeth on the rack 14 the pawl 15 engages the next set of teeth below on the rack 14 and thus establishes a new limit for the backward movement or recoil of the 75 drill slightly above the previous limit.

It will be seen from the above description that there has been provided a combination of air and jump feeding device which will not only operate efficiently under all conditions, but will be lighter in weight than the older forms of air feeds due to its smaller diameter of the feed cylinder and piston and in addition will use less air than previous forms due to the fact that with the 85 present invention it is possible to use a cylinder 13 somewhat smaller in diameter than in older forms of air feeding means.

It is to be understood that while the present showing and description disclose only 90 one specific embodiment of this present invention, other forms and modifications are included within the spirit and scope thereof, as expressed in the appended claims.

What I claim is:

1. In a percussive tool having in combination, air feeding means and an auxiliary feed device comprising a rack attached to 100 said percussive tool, and a pawl adapted upon engaging said rack to permit a slight retrograde movement of said tool relative to said rack.

2. In a combined air and jump feeding means for percussive tools, an air feed cylinder provided with a piston, a rack attached to said percussive tool extending through said cylinder to said piston provided with an air supply passage for said air feed cylinder, and a pawl mounted upon 105 said air feed cylinder adapted to yieldingly engage said rack permitting a slight retrograde movement of the tool.

3. In a combined air and jump feeding device for percussive tools, an air feed cylinder, a rack within said cylinder, said rack being attached to said percussive tool and provided with an air supply passage for 115 said cylinder extending throughout its length and having a feed piston upon its end, and a pawl mounted to slide obliquely upon the air feed cylinder engaging said rack.

4. In a combined air and jump feeding device for percussive tools, an air feed cylinder, a piston operating within said cylinder, a rack attached to said piston at one end and to the percussive tool at its other end and extending within said cylinder and a pawl mounted to slide obliquely upon said cylinder engaging said rack.

5. In a feeding device for percussive tools, a rack attached to said percussive tool, and a pawl mounted obliquely upon a support for said tool to permit a slight retrograde 5 movement of the tool when the pawl engages a tooth of the rack.

6. In a feed device for percussive tools, in combination, a stationary support, a rack mounted upon the tool and a pawl mounted 10 to slide obliquely in said stationary support for said tool to permit a slight retrograde movement of the tool when the pawl engages a tooth of the rack.

7. A feed device for hammer drills and 15 the like, consisting of a feed cylinder, a feed piston operating therein, a piston rod connected to said feed piston and extending beyond the end of said feed cylinder, a rack on said piston rod, a pawl carried by said 20 feed cylinder to engage said rack, permitting a slight retrograde movement of said rack relative to said feed cylinder after the pawl enters the space between two teeth of the rack and means for supplying motive 25 fluid under pressure to the said feed cylinder below said feed piston.

8. In a feed device for percussive tools, a rack having one end secured to a per-

cussive tool, a feed piston secured to the other end of said rack, a feed cylinder surrounding said feed piston, a pawl carried by said feed cylinder and engaging said rack, said pawl and rack being so shaped as to permit a slight retrograde movement of said rack after the teeth on said rack and 30 pawl engage and means for supplying fluid under pressure to said feed cylinder below said feed piston, substantially as shown and described.

9. In a feed device for percussive tools, 40 a rack having one end rigidly secured to a percussive tool, a feed piston secured to the other end of said rack, a feed cylinder surrounding said feed piston and said rack, a pawl carried by said feed cylinder and en- 45 gaging said rack, said pawl being so formed and mounted as to permit a slight retrograde movement of said rack after the teeth on said rack and pawl engage and means for supplying fluid under pressure to said 50 feed cylinder behind said feed piston, substantially as shown and described.

In testimony whereof, I have hereunto set my hand.

LEWIS C. BAYLES.

Copies of this patent may be obtained for five cents each, by addressing the "Commissioner of Patents, Washington, D. C."

It is hereby certified that in Letters Patent No. 1,299,814, granted April 8, 1919, upon the application of Lewis C. Bayles, of Easton, Pennsylvania, for an improvement in "Feeding Means for Drills," an error appears in the printed specification requiring correction as follows: Page 2, line 110, claim 2, strike out the word "yieldingly;" and that the said Letters Patent should be read with this correction therein that the same may conform to the record of the case in the Patent Office.

Signed and sealed this 27th day of May, A. D., 1919.

[SEAL.]

R. F. WHITEHEAD,
Acting Commissioner of Patents.
